US0D1094908S

(12) **United States Design Patent** (10) **Patent No.:** **US D1,094,908 S**
(45) **Date of Patent:** **** Sep. 23, 2025**

(54) **COVER OF A FLUID CONTROL VALVE ASSEMBLY FOR FIRE PROTECTION SYSTEMS**

(71) Applicant: **Viking Group, Inc.**, Caledonia, MI (US)

(72) Inventors: **Martin H. Workman**, Delton, MI (US); **Ori Levin**, Petach-Tikva (IL); **Svetlana Sulema**, Haderah (IL); **Guy Levin**, Herzliya (IL)

(73) Assignee: **Viking Group, Inc.**, Caledonia, MI (US)

(**) Term: **15 Years**

(21) Appl. No.: **29/861,389**

(22) Filed: **Nov. 29, 2022**

(57) **CLAIM**

The ornamental design for a cover of a fluid control valve assembly for fire protection systems as shown and described.

DESCRIPTION

FIG. 1 is a front perspective view showing a cover of a fluid control valve assembly for fire protection systems in accordance with our new design;

FIG. 2 Is A Front View thereof;

FIG. 3 Is A Left Side View thereof;

FIG. 4 Is A Right Side View thereof;

FIG. 5 Is A Top View thereof; and,

FIG. 6 Is A Bottom View thereof.

The back view of the cover of a fluid control valve assembly for fire protection systems does not constitute part of the claimed design.

The shading lines in the drawings show contour and are not intended to indicate surface ornamentation.

1 Claim, 4 Drawing Sheets
